UNITED STATES PATENT OFFICE.

EGBERT H. GOLD, OF CHICAGO, ILLINOIS.

EXPANSION-TRAP.

SPECIFICATION forming part of Letters Patent No. 752,219, dated February 16, 1904.

Application filed April 6, 1903. Serial No. 151,320. (No model.)

To all whom it may concern:

Be it known that I, EGBERT H. GOLD, a citizen of the United States, residing at Chicago, in the county of Cook and State of Illinois, have invented certain new and useful Improvements in Expansion-Traps, of which the following is a specification.

My invention relates to improvements in automatic expansion-traps for the discharge of the water of condensation from heating systems, and is especially adapted for use in connection with heating systems of railway-cars.

My invention relates to that type of trap in which the trap is opened by the contraction of an expansion device caused by its exposure to the atmosphere and is closed by the expansion of the expansion device resulting from the heat of the steam which escapes from the trap and comes in contact with the expansion device or expansion-chamber after the water of condensation has been discharged from the trap. In practice, especially in the use of such traps upon railway-cars, it is found that if the expansion device or diaphragm is wholly exposed to the atmosphere the tendency is for the expansion device to become so chilled that it will not be promptly or effectively closed by the escaping steam, with the result that there is a great loss of steam from the heating system. This is especially true in the use of these devices in connection with car-heating systems where the expansion device is exposed beneath the car, and so is exposed to a strong current of cold air. To overcome this, the diaphragm has been inclosed within a chamber which connects by a suitable passage-way with the trap, so that the water of condensation flows through this discharge passage-way into the expansion-chamber over the expansion device and thence out through openings in the bottom of the expansion-chamber. As soon as the trap is emptied of water the live steam follows a like course and coming in contact with the expansion device causes its prompt expansion and the prompt shut off of steam. If, however, the diaphragm is wholly inclosed except for the discharge-ports through the expansion-chamber, there will

be a tendency for the diaphragm-chamber to become so heated that the expansion device will not contract promptly, and there is a consequent undesirable accumulation of water of condensation in the heating system.

It is the object of my invention to provide means for overcoming these objections in either direction and also to provide means for adapting the device to different conditions of atmospheric temperature. These and such other objects as may hereinafter appear are attained by the devices illustrated in the accompanying drawings, in which—

Figure 1 is a sectional view of a trap provided with my improvements. Fig. 2 is a sectional detail of an imperforate expansion-chamber and attached parts with the diaphragm removed. Fig. 2½ is a similar view with the bottom plate swung open. Fig. 3 is an elevation of the expansion-chamber. Fig. 4 is a sectional view of the expansion-chamber on the line 4-4 of Fig. 3 looking in the direction indicated by the arrows. Fig. 5 is a sectional plan view of a modification. Fig. 6 is a detail plan view of a modification. Fig. 7 is a plan view of the under side of the modification; and Fig. 8 is a sectional detail of a car, showing the preferred manner of applying my improved trap thereto.

Like letters of reference indicate the same parts in the several figures of the drawings.

In Fig. 1 I have shown a familiar form of expansion-trap—such, for instance, as that shown and described in my Patent No. 492,495. Leading from the trap proper is a tube A, constituting a discharge-opening for the escape of the water of condensation and leading to the interior of the expansion-chamber B, within which rests the expansion device C. Resting upon the upper face of the expansion device C, which is here shown in the form of a hermetically-sealed diaphragm containing a volatile liquid, is a valve-stem D, leading to the automatic valve controlling the discharge of water from the trap. Hinged to the bottom of the expansion-chamber B is the bottom plate E. The bottom plate E is provided with openings e for the escape of water of condensation to the atmosphere. The bottom plate E is provided on

its under side with wings F, which are arranged to converge toward the openings e. Preferably these wings F are three or more in number and extend radially from the center to the periphery of the bottom plate E. With this arrangement it is evident that whatever the position of the expansion-chamber may be at least two of the wings will be turned in a direction so as to catch the air, whether it be that of the wind blowing while the train is at a standstill or the current due to the passage of the train, and consequently the air will be directed by these converging wings into the openings e, with the result that there will be a greater volume of air passing through the expansion-chamber B and in contact with the under side of the diaphragm C than would otherwise be the case, and as a result there will be a more rapid cooling and contraction of the diaphragm. These wings or similar means for conducting air into the interior of the expansion-chamber constitute one feature of my invention and in many situations will be sufficient. In order, however, to make the device adjustable to varying atmospheric conditions without varying the tension upon the diaphragm, I prefer also to provide the vertical wall G of the expansion-chamber with openings g to insure the still freer passage of air through the expansion-chamber and the consequent rapid cooling and contraction of the diaphragm. Inasmuch as in extreme cold weather such additional volume of air passing through the diaphragm might unduly cool the diaphragm and keep it so cooled as to prevent its effective and prompt expansion by the escaping steam when the trap should be opened, I provide a perforated slide H, mounted upon the vertical wall G of the expansion-chamber and arranged to be operated by a button h, by means of which slide the openings g may be partially or entirely closed at will. I am thus enabled to adjust the operation of my trap to varying atmospheric conditions by ad-

mitting a greater or less flow of atmospheric air through the expansion-chamber.

In Figs. 5, 6, and 7 I have shown a modification of my invention which may be used instead of or as supplemental to the structure shown in Figs. 3 and 4. In said modification I provide the bottom plate E' with a pivotally-mounted disk I, provided with openings i, arranged to register with openings e' in the bottom of the plate E', said disk being provided with any convenient means for rotating it upon its center, so as to close the openings e' to such an extent as may be desired in adjusting the operation of the trap to existing atmospheric conditions.

I claim—

1. A trap comprising a valve, an expansion device, operative connections between said valve and said expansion device, a housing for said expansion device, openings into said housing, and projections arranged externally of said housing so as to direct a flow of air into said housing through said openings.

2. In an expansion-trap, the combination with the expansion device, of a housing, openings through the bottom of said housing, and ribs arranged externally upon the bottom of said housing so as to catch the air and direct its flow into some of said openings.

3. In an expansion-trap, the combination with the expansion device, of a housing, provided with openings through its bottom, of projections arranged externally of said housing and radially of the bottom thereof to direct the flow of air into said housing.

4. In an expansion-trap, the combination with the expansion device, of a housing provided with openings leading to the atmosphere, of means for wholly or partially closing said openings.

EGBERT H. GOLD.
